ATTORNEY.

UNITED STATES PATENT OFFICE.

VAN V. CURTIS, OF FOLLANSBEE, WEST VIRGINIA.

AUTOMOBILE-JACK.

1,390,090.

Specification of Letters Patent.

Patented Sept. 6, 1921.

Application filed April 9, 1921. Serial No. 459,952.

To all whom it may concern:

Be it known that I, VAN V. CURTIS, a citizen of the United States of America, and resident of Follansbee, county of Brooke, 5 and State of West Virginia, have invented certain new and useful Improvements in Automobile-Jacks, of which the following is a specification.

This invention relates broadly to lifting jacks, and it has for its object to provide a simple quick-acting form of jack designed for automobile use and which is particularly adapted to be employed in lifting cars of light weight.

15 A further object is to provide a jack of the character mentioned which provides for effecting elevation to the full limit of which it is capable by a single elevating movement of the operating lever.

20 With these and other objects in view, the invention resides in the features of construction, arrangement of parts and combinations of elements which will hereinafter be fully described, reference being had to the accompanying drawings, in which —

Figure 1 is a sectional elevation of the invention;

Fig. 2 is a side elevation showing the movable standard member in an intermediate 30 lifting position; and

Figs. 3 and 4 are front and rear elevations, respectively.

The invention comprises a standard composed of two sections 1 and 2 having hinged 35 connection, interfitting lugs 3 and 4 carried on the front faces of said sections being connected by a pivot pin 5. The lower section 1 is stationary on a base 6, while the upper section 2 is adapted for movement on said 40 pivot pin to and from its normal position in which it seats upon the section 1 in vertical alinement with the latter. In its forward swung position the upper section 2 has its head disposed on a lower level than in 45 the upright position thereof; consequently, a car axle or other object beneath which the head of said section 2 is introduced may be elevated on the jack to the level occupied by said head when said section 2 is in upright position. Carried on the rear portion of 50 the under side of the upper section 2 is a downwardly and forwardly extending rack-bar 7 of arcuately curved form, which is movable with said section 2 as the latter is 55 swung to and from its normal upright po-

sition, said rack-bar being received in a channel or passage 8 provided therefor in the lower section 1. Arranged to coöperate with said rack-bar is a dog or pawl 9, the same being mounted in said passage 8 upon 60 a pivot pin 10 and occupying a downwardly and forwardly inclined position for engaging teeth formed on said rack-bar, whereby chance movement of the section 2 in a forward direction is prevented.

Loosely mounted intermediate its ends 65 upon pin 11 carried by bearing lugs 12 formed on the rear face of the upper standard section 2 is an operating lever 13. When in operative position said lever has its inner end received within a recess or chamber 14 provided therefor in said upper section. The upper face of said inner end of the lever directly underlies a bearing shoulder 15, so that downwardly directed 70 force applied to the outer end of the lever, when said upper section is in forwardly swung position, acts to swing said section toward its upright position.

When the jack is not in use the lever 13 75 is preferably disposed in a vertical position closely adjacent to the standard, as shown in dotted lines in Fig. 1. To adjust it to said position, the lever is slipped laterally on its pivot pin 11 until its inner end 80 enters a vertically elongated side chamber 14^a, whereupon the lever swings unobstructedly to its vertical position due to the absence from said side chamber of any part corresponding to the shoulder 15.

85 From the foregoing it will be apparent that I provide a jack which may be advantageously employed for lifting the axles of light-weight automobiles and the like throughout short distances by a single elevating movement of the operating lever.

90 What is claimed is—

1. An automobile jack comprising a standard composed of hinged sections, the lower section having a passage therein, a curved 100 rack-bar carried by the upper section and movable through said passage with rocking movement of said upper section, a pawl arranged to coöperate with said rack-bar, and an operating lever carried by said upper section.

2. An automobile jack comprising a standard composed of two sections, one superposed on the other, a pivotal connection between said sections permitting the upper sec- 110

tion to be rocked to and from upright seating relation to the lower section, an arcuately curved rack-bar carried by one of said sections, a pawl carried by the other section 5 for engaging the teeth of said rack-bar to limit the forward rocking movement of the upper section, and an operating lever carried by said upper section.

3. An automobile jack comprising a stand-10 ard composed of two sections, one super-posed on the other, a pivotal connection be-tween said sections permitting the upper sec-tion to be rocked to and from upright seat-ing relation to the lower section, an arcu-15 ately curved rack-bar carried by one of said sections, a pawl carried by the other section for engaging the teeth of said rack-bar to limit the forward rocking movement of the upper section, the upper section having an 20 operating chamber in the rear part thereof with an overlying shoulder and having a communicating side chamber of vertically elongated form, an operating lever pivoted intermediate its ends on said upper section 25 and having its inner end received in said

operating chamber in underlying abutting relation to said shoulder, said lever being laterally shiftable into said side chamber to permit unobstructed movement of said lever to vertical inoperative position. 30

4. An automobile jack comprising a stand-ard composed of hinged sections, the lower section having a passage therein, a curved rack-bar carried by the upper section and movable through said passage with rocking movement of said upper section, a pawl ar-ranged to coöperate with said rack-bar, an operating lever pivotally mounted on said upper section and laterally shiftable, said lever being operatively disposed when in one 35 position and being movable to a vertically disposed inoperative position when shifted laterally from the first-mentioned position. 40

In testimony whereof, I affix my signature in presence of two subscribing witnesses.

VAN V. CURTIS.
